Primary Examiner — Marissa J. Cash*Assistant Examiner* — Kayla Marie Bennett(74) *Attorney, Agent, or Firm* — ScienBiziP, P.C.(57) **CLAIM**

The ornamental design for an end cap for tension curtain rod as shown and described.

DESCRIPTION

FIG. 1 is a front, right and top perspective view of an end cap for tension curtain rod, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a cross-sectional view of the end cap for tension curtain rod of FIG. 1, taken along section line 9-9 as depicted in FIG. 5; and,

FIG. 10 is another front, right and top perspective view of the end cap for tension curtain rod shown in an environment of use.

The broken lines shown in FIG. 10 are for environmental purposes only and form no part of the claimed design.
